(57) **CLAIM**

The ornamental design for a solar panel as shown and described.

DESCRIPTION

FIG. 1 is a front perspective view of a solar panel showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the encircled portion 9 indicated in FIG. 1;

FIG. 10 is an enlarged view of the encircled portion 10 indicated in FIG. 1;

FIG. 11 is an enlarged view of the encircled portion 11 indicated in FIG. 2;

FIG. 12 is a rear perspective view of the solar panel of FIG. 1 showing the kickstand in a first alternative position.

FIG. 13 is a rear perspective view of the solar panel of FIG. 1 showing the kickstand in a second alternative position; and,

FIG. 14 is a rear perspective view of the solar panel of FIG. 1 showing the kickstand in a third alternative position.

The even-length broken lines shown in the drawings are included for the purpose of illustrating portions of the solar panel that form no part of the claimed design. The dashed-dot broken lines depict the boundaries of the enlarged portion views in FIGS. 1, 2, 9, 10 and 11 and form no part of the claimed design.
